United States Patent Office

Des. 202,993

Patented Nov. 23, 1965

202,993

HOLDER FOR A DETACHABLE STRIP OF ABRASIVE MATERIAL OR THE LIKE

John F. Stokes, 6034 Almeda, Corpus Christi, Tex.

Filed Nov. 15, 1963, Ser. No. 77,446

Term of patent 14 years

(Cl. D37—1)

FIGURE 1 is a perspective view of a holder for detachable strip of abrasive material or the like, showing my new design; and

I claim:

The ornamental design for a holder for a detachable strip of abrasive material or the like, as shown.
